UNITED STATES PATENT OFFICE.

HAROLD H. OZANNE, OF EMMETSBURG, IOWA, ASSIGNOR OF ONE-THIRD TO LEONARD VAUGHAN AND ONE-THIRD TO LAURENS D. POTTER, BOTH OF EMMETSBURG, IOWA.

DISPENSING NIPPLE.

Application filed July 30, 1923. Serial No. 654,636.

To all whom it may concern:

Be it known that I, HAROLD H. OZANNE, a citizen of the United States, and a resident of Emmetsburg, in the county of Palo Alto and State of Iowa, have invented a certain new and useful Dispensing Nipple, of which the following is a specification.

The object of my invention is to provide a dispensing nipple especially adapted for 10 use in dispensing of tooth paste, shaving cream, glue or any other semi-liquid material ordinarily packed in tube containers.

More particularly, my object relates to a 15 nipple adapted to be secured to the threaded end of an ordinary tube container used for tooth paste or the like wherein the contents of the tube container may be dispensed through the nipple without the necessity of removing a cover member and yet when the 20 nipple is not engaged the opening therein will be closed and the entire nipple will serve as a cover for the container.

Still a further object is to provide an applicator portion on the nipple wherein the 25 commodity dispensed from the container may be applied to a tooth brush or the like, depending upon the commodity dispensed.

Still a further object is to provide a flat 30 surface on two of the sides of the nipple, arranged at right angles to the opening line or slot in the nipple so that when the nipple is engaged between the fingers, there will be assurance that the opening or slot will spread to open position for permitting the contents 35 to be expelled.

With these and other objects in view, my 40 invention consists in the construction, arrangement and combination of the various parts of my device, whereby the objects contemplated are attained, as hereinafter more fully set forth, pointed out in my claims, and illustrated in the accompanying drawings, in which:

Figure 1 is a perspective view of a tube 45 container with my improved dispensing nipple shown attached thereto.

Figure 2 is a top, plan view of the dispensing nipple.

Figures 3, 4, 5, and 6 are perspective views 50 of slightly different forms of dispensing nipples.

Figure 7 is a sectional view taken on line 7-7 of Figure 3.

Figure 8 is a sectional view taken on line 55 8-8 of Figure 3; and

Figure 9 is a sectional view of a nipple portion shown in Figure 8 with the exception that the bulb portion thereof is shown with a greater capacity.

In the accompanying drawings, I have 60 used the reference numeral 10 to indicate generally a tube container which is made of comparatively thin metal which has its lower end bent and crimped over, as at 11, for forming a closure for one end of the container.

The opposite end of the tube container is provided with a cone shaped portion 12 terminating into a neck 13. The neck 13 is screw threaded for ordinarily receiving a 70 cover member or cap. The parts just described are of the ordinary construction of container used in connection with dispensing of semi-liquid materials, such as tooth paste, shaving cream, vanishing cream or the like. 75

My invention consists of a nipple member A preferably formed of rubber. The nipple member A is secured to a cap member 14, which is provided with a central opening having screw threads 15. The screw threaded portion 15 of the cap 14 is designed to 80 coact with the screw threaded neck on the container 10.

The opening in the cap 14 is contracted, as 85 at 16, so that it will require some force on the container 10 to move the contents thereof into the nipple A as will hereinafter be explained.

The cap 14 is provided with a knurled finger engaging bead 17 and is also provided 90 with an annular groove 18. The groove 18 is designed to receive the lower end of the nipple A so that the flange 19 formed on the cap 14, when bent over, will substantially grip the nipple A for holding the nipple A and the cap member 14 together. 95

The parts just described are clearly illustrated in Figures 7 and 8 of the drawings.

The nipple A is provided with a pair of 100 flat sides 20 so that it may be properly engaged between two of the fingers of the hand. The nipple A as shown in Figures 1, 3, 7, and 8 of the drawings is arranged with an upwardly extending applicator part 21. The applicator part 21 is provided with 105 a slot or opening 22, which runs lengthwise or at right angles to the flat sides 20.

The tube 10 when rolled up or pressure applied thereto, will force the contents 110 therein into the nipple A. When pressure

is exerted against the flat sides 20 of the nipple, it will cause the slot or opening 22 to spread out, as shown in Figure 2 of the drawings, wherein the contents from 5 within the nipple will be expelled.

The upwardly extending part 21 serves as an applicator for applying the ribbon of paste or shaving cream to any suitable brush or the like.

10 As soon as pressure is relieved from the nipple 20 the parts will assume the position shown in the drawings at which time the opening 22 will practically be sealed and the contents from within the container 15 will not pass out.

When it is desired to fill the nipple A, then the tube 10 is rolled up or pressure applied thereto.

In Figure 4 of the drawings, I have 20 shown the nipple similar to the nipple shown in Figure 3 with the exception that the applicator part 21 is omitted. In Figure 4 of the drawings, the slot or opening 22 is formed in the upper end of the nipple.

25 In Figure 5 of the drawings, I have shown the applicator 21 as inclined to one side and in Figure 6 of the drawings, I have shown the slot 22 shown in one side of the nipple proper.

30 In Figure 9 of the drawings, I have shown the nipple as made of comparatively thin material so that the contents placed within the nipple may be more than the style of nipple shown in Figures 4 and 8.

35 It may be mentioned that the style of nipple may be varied somewhat so that if the same is used in connection with tooth paste, there will be a sufficient amount of tooth paste within the nipple for one 40 "using."

The arrangement of the flat sides 20 insures the proper engagement of the nipple so that the slot 22 will be opened for permitting the contents within the nipple to 45 be expelled.

The nipple is formed of such material as will permit it to normally be closed and to require a positive engagement before it will open and permit the contents from the 50 nipple to be expelled.

My improved dispensing nipple may be

used as an attachment or may be sold with the tube of tooth paste or the like originally.

The use of my dispensing nipple eliminates the necessity of removing the cover or cap from the tube 10 whenever it is desired to get some of the contents from the container.

Some changes may be made in the construction and arrangement of the various parts of my invention, without departing from the real spirit and purpose of my invention and it is my intention to cover by my claims, any modified forms of structure 65 of use of mechanical equivalents which may be reasonably included within their scope.

I claim as my invention:

1. In combination with a tube container having screw threaded neck, a dispensing 70 nipple, said dispensing nipple comprising a cap member having a contracted central opening therein, a portion of said opening being screw threaded for engagement with the screw threaded neck on said tube container, a pliable nipple portion on said cap member, said nipple portion having a pair of flat sides and a slit opening wherein the contents within the nipple portion may be expelled through said slit opening by engagement of the flat sides, said flat sides being arranged at right angles to the slit opening.

2. In combination with a tube container having screw threaded neck, a dispensing 75 nipple, said dispensing nipple comprising a cap member having a contracted central opening therein, a portion of said opening being screw threaded for engagement with the screw threaded neck on said tube container, a pliable nipple portion having a pair of flat sides and a slit opening arranged at right angles to the flat sides 80 wherein the contents within the nipple portion may be expelled through said slit opening by pressure on the flat sides and said pliable nipple returning to normal position 85 when the pressure is withdrawn from the sides thereof.

Des Moines, Iowa, July 17, 1923.

HAROLD H. OZANNE.
